WOMAN'S HANDBAG

Thomas E. O'Neill, Hollywood, Calif.

Application May 16, 1955, Serial No. 36,005

Term of patent 14 years

(Cl. D87—3)

Fig. 1.

Fig. 2.

Fig. 3.

Fig. 1 is a front elevational view of a woman's handbag showing my new design;

Fig. 2 is a side elevational view thereof; and

Fig. 3 is a plan view thereof.

The side opposite that shown in Fig. 1 is substantially plain.

I claim:

The ornamental design for a woman's handbag, substantially as shown and described.
